CLAIM

The ornamental design for a pharmaceutical tablet dispenser, as shown and described.

DESCRIPTION

FIG. 1 is a top plan view of a pharmaceutical tablet dispenser showing my new design;

FIG. 2 is a top plan view of a second modified embodiment; the only difference being the number of tablets;

FIG. 3 is a right side elevational view of FIG. 1, the side opposite being a mirror image of the side shown; and

FIG. 4 is an end elevational view of FIG. 1, the opposite side being a mirror image of the end shown.

The undisclosed bottom of the dispenser is flat and unornamented.
